UNITED STATES PATENT OFFICE

168,335

STIRRING SPOON

Eric Leopold Hugo Cosby, London, England

Application July 1, 1952, Serial No. 20,437
In Great Britain January 17, 1952

Term of patent 14 years

(Cl. D44—29)

To all whom it may concern:

Be it known that I, Eric Leopold Hugo Cosby, a subject of the King of Great Britain, residing at London, England, have invented a new, original, and ornamental Design for a Stirring Spoon, of which the following is a specification, reference being had to the accompanying drawings, forming a part thereof.

Fig. 1 is a perspective view of a stirring spoon embodying my new design.

Fig. 2 is a bottom view thereof.

Fig. 3 is a side view thereof, and

Fig. 4 is a fragmentary plan view thereof.

I claim:

The ornamental design for a stirring spoon, as shown.

ERIC LEOPOLD HUGO COSBY.
